UNITED STATES PATENT OFFICE.

ANTON KOHLENBRAND, OF BUXTON, IOWA.

SHADE-ROLLER AND CURTAIN-POLE BRACKET.

1,333,426.

Specification of Letters Patent.

Patented Mar. 9, 1920.

Application filed July 25, 1919. Serial No. 313,269.

To all whom it may concern:

Be it known that I, ANTON KOHLENBRAND, a citizen of the United States, residing at Buxton, in the county of Monroe and State of Iowa, have invented new and useful Improvements in a Shade-Roller and Curtain-Pole Bracket, of which the following is a specification.

The object of the invention is to provide a device of the above mentioned character which may be readily and quickly attached to a window frame for the joint support of both a shade roller and a curtain pole. The device is so constructed that it will not mar the window frame and provision is made for adjustment to suit various widths of window frames. Likewise provision is made for the adjustment of the shade roller supporting means so that these may be set to receive the specified width of shade irrespective to the adjustment that is necessary to adapting the device on the frame to which it is to be applied.

The invention is illustrated and described in a specific embodiment to which, however, it is not to be restricted. The right is reserved to make such changes or alterations as the actual reduction to practice may suggest, in so far as such changes or alterations are compatible in spirit with the annexed claims.

In the accompanying drawings:

Figure 1 is a top plan view of the invention showing it applied to a window frame which is shown in section.

Fig. 2 is a perspective view of one end portion of the improved device.

Fig. 3 is a perspective view of that portion of the device supporting the shade roller bracket.

Fig. 4 is a detail plan view of an intermediate portion of the device to show the accessible spring which maintains it in position when once attached.

Fig. 5 is a section on the line 5—5 of Fig. 2.

Referring to the drawings, the improved support comprises a pair of tubular members 1 and 2. The tubular member 1 has fixedly attached therein a rod 3 which protrudes from one end of the said tubular member and enters the adjacent end of the tubular member in which the latter tubular member 1 slidingly engages. A compression spring 4 surrounds the rod 3 and has

its opposite ends abutting the facing ends of the tubular members 1 and 2. The rod 3 is designed for longitudinal movement in the tubular member 2 but in order to limit the length of its movement a longitudinal slot 5 is provided in the said tubular member and through this slot there projects a pin 6 which is attached to the rod 3. Obviously the rod may move a distance equal to the length of the slot but it is precluded from further movement and the spring 4 operates to hold the pin 6 adjacent one end of the slot, when the device is not attached to a window frame; but when the device is so attached the spring operates to force the two portions against the opposite sides of the frame to maintain the device in position thereon. Each tubular member carries a combined retaining means and curtain pole support made from a single rod which is formed to provide a shank 7 which enters the tubular member at the end opposite that which the rod 3 enters. This shank connects with the right angularly disposed portion 8 which is surrounded by a sleeve 9 of rubber or other non-abrasive material. This right angularly disposed portion is designed to bear against the side face of the window frame, as clearly shown in Fig. 1. The right angularly disposed portions 8 of the two rods, therefore, bear against the facing side edges of the window frame—that is, they cause their sleeve members 9 to effect such a bearing, the spring 4 providing the pressure necessary to maintain the bearing contact firm. The rod forming the curtain pole support is bent at right angles to the right angularly disposed portion to provide a section 10 running in the direction of the length of the tubular members 1 and 2, but because of the right angularly disposed portion 8, this section 10 is opposite from the said tubular members. The rod is again bent to provide the upstanding portion 11 and is still further bent to provide the curtain pole supporting portion 12 connecting with the portion 11.

The section 10 of the rod provides a supporting means for the shade roller bracket support and this latter support is made of a single plate bent back on itself to provide the two spaced sections 13, the end section 14 and the two end sections 15. The end section 14 is provided with a hole through which the section 10 of the rod passes and the two end sections 15 overlap each other

and they are recessed from their edges so that the two recesses provide an appropriate eye through which the section 10 of the rod may pass. One of the sections 13 5 of the plate carries a rubber or non-abrasive latch 16 which, when the device is attached to a window frame, lies against the front face of the inside architrave thereof. The other of the sections 13 is provided 10 with a longitudinal slot 17. An appropriate bolt 18 passes through this slot to secure the shade roller bracket 19 to the front section, the shade roller bracket being provided with a teat or lug 20 also entering the slot 15 17, this teat obviously serving to prevent pivotal movement of the shade roller bracket on the bolt. The slot 17 provides for the adjustment of the shade roller bracket along its attendant support and the two may thus 20 be positioned to accommodate any desired width of shade. On the end section 14 of each of the shade roller supports there is provided a spur like plate 21 the nose of which rests against the inner face of the 25 window frame to preclude the weight of the curtain pole and the shade roller pulling those portions of the device down, such as might be the case were the bearing surfaces of the sleeves 9 relied upon solely to maintain 30 that portion of the device standing against the inside face of the window frame in the same plane with that portion of the device set in between the two vertical stiles thereof.

35 To provide for adjusting the device to accommodate different widths of window frame, the shanks 7 of the curtain pole supporting rods are loosely engaged in their respective tubular members 1 and 2 except 40 when the set screws 22 which threadingly engage the tubular members bear firmly against these shanks. Obviously the loosening of the set screws provides for longitudinal adjustment of the shanks, to increase 45 or decrease the length of the device as a whole. Thus the range of action of the spring 4 may be relatively small and yet the device may be adapted for various widths of window frame simply by the

proper adjustment of the shanks 7 in their 50 respective tubular members.

From the foregoing description and the accompanying drawings, it is believed that a clear enough understanding of the invention is to be had to render further description 55 unnecessary.

The invention having been described, what is claimed as new and useful is:

1. A device of the kind described comprising a pair of tubular members, a rod 60 carried by one of said tubular members and slidably entering the other, a compression spring surrounding the rod and bearing against the opposed ends of the tubular members, curtain pole brackets formed of 65 a single rod and bent to provide shanks entering the tubular members at the ends opposite from that which the first said rod enters, the shanks connecting with right angularly disposed portions bearing against 70 the inner facing sides of a window frame, and means for adjusting the shanks relative to the tubular members so as to increase or diminish the length of the device as a whole to adapt it for attachment to different 75 widths of window frames.

2. In a device of the kind described, a pair of tubular members, a rod mounted in one tubular member and slidably entering the other, a spring in surrounding relation 80 to the rod and bearing against the opposed ends of the tubular members, with shanks entering the opposite ends of the tubular members, the shanks connecting with right angularly disposed portions carrying non- 85 abrasive means adapted to engage the facing edges of a window frame, and shade roller brackets adjustably supported on right angularly disposed portion, and plate like spurs carried adjacent said right angularly disposed portions for engagement with the facing side of the inner architraves of a window frame to prevent the deflection of the right angularly disposed portion from a substantially horizontal plane. 90

95 In testimony whereof I affix my signature.

ANTON KOHLENBRAND.
